UNITED STATES PATENT OFFICE.

GEORGE S. MEYER, OF NEWBURG, NEW YORK.

TELEPHONE-RECEIVER HOLDER.

SPECIFICATION forming part of Letters Patent No. 669,800, dated March 12, 1901.

Application filed December 8, 1900. Serial No. 39,156. (No model.)

To all whom it may concern:

Be it known that I, GEORGE S. MEYER, a citizen of the United States, and a resident of Newburg, in the county of Orange and State 5 of New York, have invented a new and Improved Telephone-Receiver Holder, of which the following is a full, clear, and exact description.

This invention relates to improvements in 10 telephone-receiver holders; and the object is to provide a simple device of this character by means of which the receiver will be supported in listening position near the transmitter, leaving a person's hands free for holding paper and making notes thereon while 15 holding conversation over the telephone.

I will describe a telephone-receiver holder embodying my invention and then point out the novel features in the appended claim.

20 The figure of the drawing is a perspective view of the telephone-transmitter, showing a device embodying my invention attached thereto.

25 Referring to the drawing, 1 designates the arm for the telephone-transmitter 2, and 3 indicates the receiver. The holding device consists of a bar 4, of metal or other suitable material, having between its ends a loop 5, designed to engage over the upper end of the 30 receiver-arm and having at its inner extremity a hook 6 for engaging around the under edge of said arm. The bar 4 extends out-

ward beyond the end of the transmitter, and at its outer end it is provided with two downwardly-extended loops 7 and 8, which together 35 form a receptacle for the receiver 3.

In use while a person is holding conversation over a telephone the receiver is to be placed in the loops 7 and 8, as indicated in the drawing, so that the end thereof will come 40 near the person's ear, thus making it convenient for the person to use both his hands in holding paper and writing thereon.

While I have shown the holding device as consisting of round wire, it is obvious that it 45 may be made of a flat or angular bar without departing from the spirit of my invention.

Having thus fully described my invention, I claim as new and desire to secure by Letters Patent—

50 A receiver-holder, consisting of a bar having a loop portion between its ends for engaging over a transmitter-arm, a hook at one end for engaging around the under side of said arm, and receiver-holder loops at the opposite ends of said bar, substantially as specified.

55 In testimony whereof I have signed my name to this specification in the presence of two subscribing witnesses.

GEORGE S. MEYER.
